CLAIM

The ornamental design for a beer bottle, as shown and described.

DESCRIPTION

FIG. 1 is a front perspective view of a beer bottle showing my new design;

FIG. 2 is a front view of the beer bottle shown in FIG. 1;

FIG. 3 is a side view of the beer bottle shown in FIG. 1;

FIG. 4 is a top view of the beer bottle shown in FIG. 1; and, FIG. 5 is a bottom view of the beer bottle shown in FIG. 1.

The broken lines showing of the bottom raised ridges are for illustrative purposes only and form no part of the claimed design.

The slanted shading shown on the bottle represents a translucent surface.
